(57) **CLAIM**

The ornamental design for a “mobile animal lifting device,” as shown and described.

DESCRIPTION

FIG. 1 is a rear top perspective view of the mobile animal lifting device shown with the lifting harness in a raised position;

FIG. 2 is a rear side perspective view thereof;

FIG. 3 is another rear side perspective view thereof;

FIG. 4 is another front side perspective view thereof;

FIG. 5 is a front perspective view thereof;

FIG. 6 is a top, rear perspective view of the mobile animal lifting device shown with the lifting harness portion removed for clarity of illustration;

FIG. 7 is a top, front side perspective view thereof; and,

FIG. 8 is a top front perspective view thereof.
